US0D1059968S

(12) **United States Design Patent** (10) **Patent No.:** **US D1,059,968 S**
(45) **Date of Patent:** **** Feb. 4, 2025**

(54) **SANDWICH CUTTER AND SEALER**

(71) Applicant: **Haiyi Li**, Shenzhen (CN)

(72) Inventor: **Haiyi Li**, Shenzhen (CN)

(**) Term: **15 Years**

(21) Appl. No.: **29/934,478**

(22) Filed: **Mar. 26, 2024**

(30) **Foreign Application Priority Data**

Mar. 15, 2024 (CN) 202430132880.2

(51) **LOC (15) Cl.** **07-04**

(52) **U.S. Cl.**

USPC **D7/674**

(58) **Field of Classification Search**

USPC D7/672-674, 693, 381, 352, 675

CPC A47J 43/20

(57) **CLAIM**

The ornamental design for a sandwich cutter and sealer, as shown and described.

DESCRIPTION

FIG. 1 is a front perspective view of a sandwich cutter and sealer showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 shows a closed view of the sandwich cutter and sealer.

The broken lines in the drawings illustrate the portions of the sandwich cutter and sealer, which form no part of the claimed design.

1 Claim, 9 Drawing Sheets
